UNITED STATES PATENT OFFICE

166,427

TOOTHBRUSH OR SIMILAR ARTICLE

Alvin E. Strock, Newton, Mass.

Application November 25, 1949, Serial No. 6,259

Term of patent 14 years

(Cl. D9—2)

To all whom it may concern:

Be it known that I, Alvin E. Strock, a citizen of the United States of America, residing in Newton, in the county of Middlesex and Commonwealth of Massachusetts, have invented a new, original, and ornamental Design for a Toothbrush or Similar Article, of which the following is a specification, reference being had to the accompanying drawing, forming a part thereof.

Fig. 1 is a top plan view of a toothbrush embodying my new design;

Fig. 2 is a side elevation;

Fig. 3 is a bottom view; and

Fig. 4 is an enlarged end view.

I claim:

The ornamental design for a toothbrush or similar article, substantially as shown.

ALVIN E. STROCK.
